UNITED STATES PATENT OFFICE.

JOHN W. ORPHY, OF ROCHESTER, NEW YORK, ASSIGNOR TO CHARLES T. HAM AND F. D. W. CLARKE, OF SAME PLACE.

LANTERN.

SPECIFICATION forming part of Letters Patent No. 229,330, dated June 29, 1880.

Application filed December 19, 1879.

To all whom it may concern:

Be it known that I, JOHN W. ORPHY, of the city of Rochester, in the county of Monroe and State of New York, have invented new and 5 useful Improvements in Lanterns, of which the following is a specification, reference being had to the accompanying drawings.

This invention relates to that class of lanterns in which the air for the support of combustion is supplied to the flame through tubes or air-conduits which are provided with air-inlets near the top of the globe or chimney, and which have their lower ends connected with an air-chamber arranged below the burner 15 and communicating therewith.

The object of this invention is to produce a simple, cheap, and compact lantern of this character in which the flame is not extinguished when the lantern is exposed to air-currents or 20 subjected to violent agitation.

My invention consists of the peculiar construction and arrangement of the air-inlets at the upper ends of the air-tubes, as will be hereinafter fully set forth.

25 In the accompanying drawings, Figure 1 is an elevation of a lantern provided with my improvement. Fig. 2 is a vertical section of the upper part of the lantern. Fig. 3 is a horizontal section in line *xx*, Fig. 1, looking upward. Fig. 4 is a horizontal section in line *zz*, Fig. 2, looking down, the air-inlets *jj* not being shown.

Like letters of reference refer to like parts in the several figures.

35 A represents the oil-vessel; B, the air-chamber arranged upon the same; C, the burner; D, the globe or chimney, and E the top or cap of the lantern, all of ordinary and well-known construction.

40 F F represent two air-tubes, arranged on the outside of the globe on diametrically opposite sides thereof, and having their lower ends connected with the air-chamber B in the usual manner. The upper ends, *f*, of the tubes 45 F F are flattened on their sides and turned inward, so as to rest against the sides of the cylindrical extension G of the globe or chimney, or the lower portion of the lantern-top,

without communicating therewith, the upper and inner sides of the extensions *f* being closed 50 or imperforated.

h is an air-inlet opening formed in the lower side of the inwardly-turned upper portion, *f*, of each air-tube F, between the descending portion of the latter and the side of the lantern-top. 55

I is an annular flange or shield surrounding the lantern-top and arranged on a level with or slightly above the air-inlets *h*, so as to protect the latter as much as possible against the exhausting action of passing air-currents. 60 *jj* are air-inlets formed in the flattened sides of the upper portions, *f*, of the air-tubes F, above the inlets *h* and the flange I.

The aggregate area of the air-inlets *jj* in each tube is preferably made about as large as the 65 area of the air-inlet *h*, so that when the air-inlets *h* below the flange I are rendered inoperative by the exhausting action of passing air-currents the air-inlets *jj* above the flange will supply the tubes with the air necessary to 70 sustain the flame, or vice versa.

The flange I need not extend from one tube to the other; but the central portion of the flange on each side of the lantern may be dispensed with, if desired. 75

The exterior air is drawn into the tubes F through the openings *h* and *jj* by the draft of the globe or chimney, and passes down through the tubes into the air-chamber B, and thence 80 through the burner.

The gaseous products of combustion escape from the top of the lantern in the usual manner.

If desired, the plate upon which the globe or chimney rests may be provided with a small 85 number of fine openings for admitting sufficient cold air into the globe independent of the burner to prevent overheating of the globe.

My improved lantern is very simple and compact in construction and very efficient, producing a steady flame, which is practically not 90 extinguishable when subjected to such motions or exposed to such air-currents to which lanterns are subjected when in practical use.

I am aware that lanterns in which the open 95 upper ends of the air-supply tubes are not connected with the chimney and provided with

dividing plates which deflect the air into the open mouths of the tubes are not new, and I do not wish to claim such constructions.

I claim as my invention—

5 In a lantern, the combination, with the air-tubes F, of the inwardly-turned extensions f, arranged at the upper ends of the tubes and closed at their upper and inner sides, and having no communication with the chimney or gas

exit, air-inlets h, formed in the bottom plates to of the extensions f, and air-inlets j, formed in the side plates thereof, substantially as set forth.

JOHN W. ORPHY.
